UNITED STATES PATENT OFFICE

CLAIR D. LAKE AND RALPH E. PAGE, OF BINGHAMTON, NEW YORK, ASSIGNORS TO THE TABULATING MACHINE COMPANY, OF ENDICOTT, NEW YORK, A CORPORATION OF NEW JERSEY

TABULATING MACHINE

Application filed February 5, 1925. Serial No. 6,981.

The present invention covers improvements in tabulating machines, more specifically printing tabulators, and particularly of the type disclosed in copending application, Serial No. 639,153, filed May 15, 1923.

These machines, as is well known, analyze perforations in record cards and after analyzing the perforations may print on a sheet of paper all or part of the data contained on the 10 cards.

It may transmit the data from successive cards to counters, or accumulators, printing the total of data accumulated from all the cards, or from particular groups of cards if 15 they are arranged in such groups. It may print data from each card and the total of such data for each group of cards. It may also print with each item a designation of the group to which the data belongs. Other 20 combinations of similar nature may be effected.

In the machine described in the above application the recording of group numbers was effected by entering the group number into 25 an accumulator counter, then, if it was desired to print this group number, the counter was read by reading devices, and these reading devices controlled the type elements of the machine so as to print the group number.

Among the objects of our invention is the provision of means for printing the designating number of a group of cards from the first card of the group and then suppressing the 35 paper feed so that when the totals of that group are printed they are in alignment on the record sheet with the group number printed from the first card of the group.

Another object of our invention is the provision of means for printing group numbers 40 direct from the cards.

Another object is to provide means whereby all printing operations are automatically performed at comparatively slow speed and 45 all non-printing operations at much higher speed.

Another object is in provisions for printing the group number from the first card of a group while suppressing the printing of corresponding items from that card, and subse-

quently printing the total of the group in alignment with said group number.

Another object is the provision of simpler means for printing the group number from each card of a group in alignment with data 55 from that card, and then omitting the printing of said group number when the totals of said item are printed.

Another object is the use of a two speed driving motor the speed of which is automatically varied to provide comparatively low speed for printing (listing), and a higher speed for non-printing operations.

Other objects reside in the provision of a rearrangement of contacts and circuits in the 60 machine whereby the use of certain contacts heretofore employed may be obviated and whereby other contacts and circuits may be used to perform novel functions which will 65 hereinafter be set forth.

Other objects and advantages will be hereinafter set forth in the accompanying specification and claims and shown in the drawings which by way of illustration show what is now considered to be the preferred embodiment of the invention.

In the machines described in the previous application group indicating was effected by counters, the group number being entered into a counter for a first card of a group. Thereafter the entering of further group numbers into the counter was suppressed by means of group indicator contacts which opened up after the first card of a group.

In the machine forming the subject matter 85 of the present application the necessity for said group indicator contacts for each group designating column is obviated. In place of entering group numbers upon a counter or counters the group number as taken from the 90 card is arranged to directly control the printing mechanism of the machine. The feature of suppressing the entering of items into the accumulator by the group indicator contacts after the passage of the first card, is 95 obviated. Group numbers may or may not be entered into the accumulator but, if entered, these group numbers will be accumulated therein, there being no suppression of the accumulation of group numbers.

With our present machine provision is made for varying the speed of operation when the tabulator is running as a straight tabulator without listing. In other words, while the first card passes through the machine and the group number is being printed therefrom provision is made for running the printing attachment at the usual printing or listing speed because otherwise the mechanism would be damaged. After the first card has passed and the group number is printed the machine automatically assumes a higher speed for tabulating the remainder of cards in that group.

15 In the drawings,

Fig. 1 is a front view of a tabulator embodying our improvements.

Fig. 2 is a top plan view of the same on a slightly larger scale.

20 Fig. 3 is a sectional view of the printing section of the machine. This section is taken substantially on line 3—3 of Fig. 5.

Fig. 4 is a detail sectional view of a certain of the controlling parts, the section being taken substantially on the line 4—4 of Fig. 5.

25 Fig. 5 is a top view, partly in section, of the parts in the base of the printer section, the magnets being removed, the section being taken substantially on the line 5—5 of Fig. 3.

30 Figs. 6 and 7 are detail views of the clutch mechanism shown in Fig. 3, in different moved positions.

Fig. 8 is a detail view of the parts for controlling the paper feed, which are located 35 behind the clutch shown in Fig. 4.

Fig. 9 is a fragmentary detail view showing the parts in moved position.

40 Fig. 10 shows the first printing operation on the sheet when the group number is printed.

Fig. 11 shows the printing operation when the record sheet shows a group number together with a set of totals.

45 Fig. 12 shows a list of items together with the group number, which is printed concurrently with each item, and following these items there are printed the totals thereof without the group number.

50 Fig. 13 shows the list-non-list lever and its controlling connections to the listing cam.

Figs. 14 and 15 show different positions of the levers which the listing cam controls.

55 Fig. 16 is a detail sectional view taken on line 16—16 of Fig. 8, and showing the devices operated by the listing lever shaft for shifting the clutch control rod.

60 Fig. 17 shows the contacts which are controlled by the listing lever when the latter is set for straight tabulating without listing of individual items.

Fig. 18 shows the other group of contacts controlled by the listing lever when the latter is set for listing items.

65 Fig. 19 is a sectional view taken substantially on the lines 19—19 of Fig. 7, showing

the parts enlarged, and with the clutch control shaft in tabulating position.

Fig. 20 is a view of the control unit of the machine shown exposed in Fig. 1 underneath the counters.

70 Fig. 21 is a sectional view taken on line 21—21 of Fig. 20.

Fig. 22 is a sectional view taken on the line 22—22 of Fig. 20, showing one of the group indicator contacts.

75 Fig. 23 is an enlarged top plan view of the listing cam shown in Fig. 13 together with other parts shown in Fig. 5 on an enlarged scale.

Figs. 24 and 25 are side and rear elevational views, respectively, of the non-print contacts shown in dotted lines in Fig. 1.

80 Figs. 26^a and 26^b taken together show an electric wiring diagram of the machine.

85 In describing the machine two conditions must be considered. The first or tabulating condition makes records of group numbers and totals only. The second or listing condition prints the individual items with the group numbers and then prints the totals of the items without the group numbers. If the machine is to be set for tabulating (totaling) items without listing the individual items, i. e., the first condition mentioned above, so that only totals and group number 90 are printed upon the record sheet, provision is made for initially printing the group number upon the sheet, as shown in Fig. 10. Subsequently, when totals have been accumulated by the machine, these totals are entered upon 100 the record sheet in alignment with the previously printed group number, as shown in Fig. 11 of the drawings.

105 The second or listing condition has a different operation. Here both group number and items are printed concurrently, the group number being repeated for each item as shown in Fig. 12. Finally totals are printed without the accompanying printing of the group number.

110 The instrumentalities for bringing these operations about, so far as the mechanism of the machine is concerned, are directed particularly to constructions involving the operation of the listing cam and the parts controlled thereby, and also the operation of the paper feed.

115 A clear understanding of the present machine will best be had by describing the operation of the previous machines upon which the present invention is an improvement.

120 In the previous machines described in the copending application above referred to, the rising of the type 266 (Fig. 3), when the machine was set for listing, was brought about by rocking shaft 305 through the instrumentality of listing cam 311. When totaling operations were to be effected, the type were raised by means of total cam 301. In 125 the former machine the listing cam 311 was 130

driven at all times when the tabulating machine was operated. If it was desired not to list the individual items but to only tabulate, i. e. print totals, provision was made for withdrawing the listing cam roller from 5 cooperation with the listing cam.

Having now described briefly the previous construction, the modified construction of the present machine will be described.

Fixed to the listing cam shaft 294, adjacent 10 the listing cam 311, is a clutch disk 500 (Figs. 3, 6 and 7) provided with a notch 501. Listing cam 311 is loose upon the listing cam shaft, and during listing operations this listing cam is clutched to shaft 294, by 15 the means which are now to be described.

Pivottally mounted upon the listing cam 311 is a clutch member 502. The clutch dog 502 is normally drawn into engagement with disk 500 by means of a spring 503 which, 20 at its opposite end, is fast to a part 504 extending over and terminating in a nose 505. The clutch dog 502 is provided with a tail or pawl portion 506, which is adapted to cooperate with a shoulder portion 507 upon 25 a rocking lever 508. Lever 508 is also provided with a supplementary pivoted latch 509 which allows the member 504 to pass it and prevents backward rebound of the same. 30 For normal listing operations, lever 508 is in the position shown in Fig. 6. With the parts in this position clutch dog 502 is in engagement with the notch 501 and this couples the listing cam 311 to the listing cam shaft 294. The lever 508 is fixedly mounted upon 35 a stub shaft 510 (see Fig. 23), which shaft is journaled in lugs 511 fixed to a bracket 512 fast to the frame of the machine. It will be understood that shaft 510 must be rocked in a counterclockwise direction to 40 allow the clutch dog 502 to engage for listing. This rocking is effected by the list and non-list shaft lever of the tabulator.

Referring now to Fig. 13: 316 is the list-non-list lever of the tabulator. This lever is fast to a rod 317, and around this rod is the usual compression spring 319 heretofore employed. As in the previous construction the shaft 317 is provided with a shifter fork 318 (Fig. 17) coacting with cross pins 320 on a shifter rod 300. The arrangement is such that by rocking lever 316 from the tabulating or non-listing position, as shown in Fig. 13, to listing position (i. e., in the direction indicated by the curved arrow), the shifter rod 300 will be shifted downwardly from the position shown in Fig. 13. In place of connecting the slip or shifter rod 300 to the follower 310, which cooperates with the listing cam 311 as in the previous construction, the follower 310 is arranged so as to be always in engagement with the cam slot in cam 311. It is entirely free of control by the shifter rod 300. Upon the end 50 of the shifter rod 300 there is provided a bevel

nose 513 (see Fig. 19), which nose, when 300 is shifted downwardly, separates two fingers 514 and 515. In Fig. 19 these parts are shown in non-separated position. Finger 515 (see Fig. 6) is fast upon a pivoted arm or lever 516, which in turn is fixed to the stub 70 shaft 510 previously referred to (see Fig. 23).

The other cooperating finger 514 is integrally disposed on a supplementary arm 517 (Fig. 23), which is substantially similar in 75 contour to 516. Arm 517, instead of being pinned to shaft 510, is loose thereon, and this arm 517 has secured thereto, preferably adjustably, a supplementary arm 518 (see Fig. 6) carrying upon its end a roller 519 80 adapted to cooperate with a notch 520 in the listing cam 311. When the shifting lever is in listing position the roller 519 is out of engagement with the notch 520, as shown in Fig. 6, but when the shifting lever is in the tabulating position this roller 519 is in engagement with the notch, in the manner shown in Fig. 7. The purpose of the roller 519 is merely to positively locate cam 311 which carries dog 502 so that 502 will drop 85 cleanly into slot 501 when shifting lever is shifted to listing position.

The foregoing has described the means for raising the type 266 during the listing or individual item printing operations. If, after 90 listing, the printing devices are to be operated to take a total a cam 301 on the so-called total printing shaft 315 rotates causing elevation of an arm 302 provided with a cam follower, which arm is loosely mounted on shaft 100 305 (Fig. 14) and is provided with an abutment 303 which is adapted to contact with an adjustment screw 303^a carried by the bell crank lever 304 thus rocking bell crank 304 in a clockwise direction and similarly rocking shaft 305. As previously described the 105 rocking shaft 305 through arms 306 (Fig. 3) is adapted to raise the type 266. To drive the total printing shaft 315 the customary 110 reset motor RM is provided and this, through a shaft and worm 339, drives a worm wheel 340. Fixed to worm wheel 340 is a ratchet disk 341 (Fig. 4). Fast on shaft 315 is a so-called printing cam 342. Fast to this printing cam is a bar 343 which in turn carries a 115 clutch dog 344. The clutch dog overlies ratchet 341 and is normally disengaged. Engagement of the dog with the ratchet is permitted when the reset clutch magnet 233 is energized. The armature 346 of this magnet 120 is pivoted at 347 and has connected to it an extended arm 348 which is notched to engage the tail of the one revolution clutch dog 344. Upon the energization of magnet 233, latch 348 is elevated and the clutch dog 344 drawn 125 by its spring into engagement with the ratchet 341. Subsequently to this engagement the printing cam and printing shaft 315 rotate in unison with the ratchet, making one revolution. During this single revolution of these 13

parts magnet 233 becomes deenergized, permitting latch 348 to reengage the clutch dog and disengage it from the ratchet 341. Part 348 is restored by a spring (not shown) and 5 also by block 349 and pin 350. As in the previous construction a rock arm 354 (Fig. 4) is provided cooperating with the cam 342, which rock arm is fixed to a total print shaft 355. The actuation of this total print shaft 10 derives the amount from the accumulators in the manner described in the previous application. The rocking of the shaft 355 serves also to rock a bail 355^a which opens certain contact devices NL¹, NL², etc., for a purpose 15 which will hereafter be described.

The foregoing has explained the general operation when the tabulator is set for straight listing followed by the taking of a total of the listed items. It will now be assumed that after such a listing run and total 20 is taken it is desired to set the tabulator for straight tabulating, omitting printing of items and printing only totals and group numbers. Figs. 10 and 11 show the report 25 which is printed under these conditions.

The first operation is to shift the tabulator list lever 316 from the listing position to non-listing or tabulating position. Fig. 13 shows the tabulator non-list lever 316 in so-called 30 tabulating position. With this condition of parts the nose 513 (Fig. 19) of the shifter rod 300 will be in the position shown in Fig. 19. Consequently finger pieces 514 and 515 will not be separated. However, upon shifting 35 the shifter lever from the previous listing position to the non-listing position the finger pieces 514 and 515 will have moved from the open position shown in Fig. 6 to the closed position shown in Fig. 3 and will have permitted arm 508 to rock from the position 40 shown in Fig. 6 to that shown in Fig. 3 with the end of member 508 on top of the sholdered tail of the clutch dog 502. At this time in the cycle the clutch dog is not disengaged 45 from the notch 501 on disk 500. It therefore follows that upon the first machine cycle 50 the listing cam 311 will make one revolution and at the completion of this revolution the dog 502 will be thrown out, assuming the 55 position illustrated in Fig. 7. This single revolution of the listing cam 311 is utilized for printing the group number on the listing sheet as shown in Fig. 10 of the drawings. As shown in Fig. 11 the totals on the record 60 sheet are eventually printed in alignment with the previously printed group number. It is therefore necessary to provide means for preventing the paper feed from the time that the group number is printed until the total 65 printing operation is completed.

After the listing cam 311 has made one revolution the clutch dog 502 is disengaged as above explained and remains disengaged until a total is taken. Upon the taking of a 65 total, magnet 233 is energized actuating arma-

ture 346 to lift the cam latch 348 out of the engagement with the cam dog 344 to permit the machine to take a total. The armature 346 and shaft 347 rock together and the rocking of shaft 347 causes an arm 352 to rock 70 clockwise (Fig. 5). Arm 352 engages a pin 621 on an arm 622 fixed on shaft 510 and thus rocks this shaft counterclockwise thereby rocking arm 508 counterclockwise, releasing dog 502 and allowing it to reengage notch 501 75 to place the parts in condition for listing the following group.

The control of the paper feeding mechanism, its construction and operation are as follows:

Link 336 at its upper end connects to a ratchet and pawl paper feed device of the usual type, and at its lower end connects to a lever 334 which is pivotally mounted at 601 on a fixed bracket plate 335. Secured to 80 334 are two L-shaped member 333 and 337 rigidly connected at their right hand ends to 334 at points 601 and 605, their other ends adjustably secured to part 334. Parts 334, 333 and 337 after being once adjusted always 85 operate as a single unit. This unit is actuated either by rocking of shaft 305 or of lever 330. Shaft 305 always operates the paper feeding mechanism when it must feed the paper on the up stroke of the type bars, as 90 for every revolution of cam 311 when listing is being performed, an also for one revolution during the first card cycle when tabulating operations are being performed. As will be shown later, lever 330 actuates lever 334 95 on the down stroke of the type bars to draw down on link 336 only during the latter part 100 of a total printing and reset cycle when the machine has been previously set for listing.

When the machine is set for listing the operation of the paper feeding mechanism is as follows: Lever 316 (Figs. 13 and 16) is shifted manually in a counterclockwise direction to listing position and, as rod 300 is moved to the right, block 603 (Figs. 8 and 16) 105 attached rigidly to shaft 317 makes contact with a projection 604 of latch 337^b which is pivotally mounted at 606, and holds latch 337^b in such position that it cannot engage block 337^a fixed to member 337. Therefore 110 parts 337^a and 337^b are inoperative while the machine is set for listing and are used as will be later explained for tabulating only. While listing, shaft 305 rocks first in a clockwise 115 and then in a counterclockwise direction for each revolution of cam 311 (Figs. 14 and 15). At the end of shaft 305 is an arm 338 having at its upper end a pin 600. As shaft 305 is rocked in a clockwise direction this pin 600 contacts against a shoulder on 120 member 337, rocking the unit comprising parts 334, 333 and 337 about its pivot 601 and drawing down link 336, thus feeding the paper one line space. This occurs while the type bars are being raised. It will be seen 125 130

that during listing operation the paper is fed one line space for each cycle of operation of the machine or each revolution of cam 311. On the down stroke of the type bars shaft 305 is rocked in a counterclockwise direction and allows lever 334 to resume its former position.

At the end of a group of cards which have been listed a total is taken. When the machine takes a total cam 311 comes to a stop and shaft 315 on which are mounted cam 301 and gear 328 makes a complete counterclockwise revolution, as previously described. Cam 301 rocks shaft 305 (Figs. 14 and 15) through the same arc as described above for cam 311, so that the paper is fed the usual one space before printing a total. Early in the second half of the total printing cycle shaft 305 completes its rocking cycle and link 336 rises to normal position as parts 334, 333 and 337 return to position shown in Fig. 8.

After a total is printed it is desirable to leave a blank space on the paper before listing the first item of the next group. The paper is fed this extra space during the last part of the total printing cycle in the following manner: A pin 329 on gear 328 contacts with lever 330 which is pivoted loosely on shaft 305, rocking 330 in a clockwise direction. Lever 330 has an upwardly extending arm 330^a to which is connected a slotted link 602. As lever 330 is rocked by pin 329 the lost motion in link 602 is taken up, stretching spring 608, and link 602 then acts on a pin fixed in part 333 of the unit consisting of parts 334, 333 and 337. This rocks the unit in a counterclockwise direction thus drawing down link 336 a second time during the total printing and reset cycle to feed the paper an extra space after total printing. The slot in link 602 and the spring 608 above mentioned are necessary to hold lever 330 normally in a counterclockwise position to provide clearance while parts 337^a, 337^b and 604 are operative as will be later described.

If it is desired to perform tabulating (as distinguished from listing) operations on the machine it is necessary to shift lever 316 to tabulating position. As has been pointed out, when the machine is set for tabulating, the listing cam 311 will turn one revolution (during the first card cycle) starting from the position shown in Fig. 3, being stopped by the arm 508 after the completion of one revolution. During this revolution the shaft 305 will be rocked and the paper fed one line space, as above described. But as the shifting of lever 316 to tabulating position has moved block 603 out of contact with projection 604 block 337^a becomes locked in position shown in Fig. 9 by latch 337^b actuated by spring 607. The spacing of the paper takes place during the early part of this cycle. During the same cycle after the spacing has taken place the printing is effected. In the

present instance, that is, during tabulating operations, this printing from the first card will be of the group designation number only. As the listing cam 311 is locked against operation at the end of the first card cycle there will be no further printing during the continued operation of the machine until a total is taken. In the meantime as the operation of the paper feed mechanism has been suppressed by the latching of block 337^a by latch 337^b the line on which the group number is printed remains in printing position so that when the total is eventually printed it is on the same line with the group number, as in Fig. 11. When the total is printed shaft 305 is again rocked in a clockwise direction, this time by cam 301, but no movement of 334 or 336 takes place on this up stroke of the type bars due to lever 337 being held by block 337^a and latch 337^b. The result is that paper is not fed at this time and the total is printed on the same line as was the indication number during the first tabulating cycle. Near the end of the revolution of shaft 315, after shaft 305 has returned to its normal position, pin 329 on gear 328 makes contact with lever 330 and causes it to rock about pivot 305 in a clockwise direction, the slot in link 602 attached to its upper end allowing it to move freely. As lever 330 nears the end of its clockwise rocking movement its upward projection 330^a acts against projection 604 of latch 337^b, releasing block 337^a and allowing 337 and attached members, including link 336, to resume normal position, with the shoulder of 337 against pin 600. As soon as pin 329 has passed the end of lever 330, spring 608 draws lever 330 to its normal position. It will be observed from the above that lever 330 has two entirely different functions to perform, depending upon whether the machine is set for tabulating or listing.

Referring now to Figs. 20 and 21, the parts show the usual group indicator and automatic control unit. As in previous machines shaft 398 is rotated in unison with the tabulator shafts during tabulating operations and arm 404 is rocked during resetting and total printing operations. 92 is the group indicator magnet. Upon the energization of this magnet latch 417 is attracted releasing arm 418 fast to bail 416 which thereupon rocks clockwise under the influence of spring 419. Cooperating with bail 416 are three contacts GI¹, GI³ and GI⁸ instead of the ten group indicator contacts heretofore employed. Contacts GI¹ and GI³ are normal open contacts and GI⁸ are closed so that upon the rocking of bail 416 under control of magnet 92 contacts GI⁸ will open and GI¹ and GI³ will close. This action occurs at or towards the end of the first card cycle of a group. Bail 416 is restored in an anticlockwise direction during the reset and total

printing cycles by means of arm 404 and shaft 400.

Contacts 71 and 73 are the usual automatic control contacts which are controlled by automatic control magnets 72. These parts being the same as in previous machines require no detailed description.

The machine is also provided with a gear transmission 257 (Fig. 1) which is shifted 10 when the tabulator is set for listing to drive the parts at the low printing speed. The transmission is provided with contacts 250 (shown on the circuit diagram) and which are closed as in the previous machines when 15 the transmission is set to drive the machine at reduced speed.

Referring now to the diagram views (Figs. 26^a and 26^b), 50 designates a stack of record cards which are adapted to be advanced one 20 at a time by means of a picker 51 into engagement with feed rolls 52. The feed rolls ultimately advance the cards to the discharge stack in the usual manner. Rolls 52 are driven by gearing generally designated 53 25 which in turn is driven by a tabulator motor TM through the usual magnetically controlled clutch 54. This clutch is controlled by clutch magnet 55. Cards are advanced past upper brushes 55^a and contact blocks 56, 30 and thereafter past lower brushes 59 and contact blocks 60. The upper and lower brushes are respectively carried by common bars 57 and 58. Upper and lower card levers 61 and 62 are provided, which card levers are respectively adapted to close upper card lever contacts 63^b and lower contacts 63^a and 64^a. From the upper and lower brushes cabled 35 wires 65 and 66 are shown leading to plug sockets on the tabulator plugboard 254. Sockets 67 are for the upper brushes and multiple sockets 68 are for the lower brushes. On the plugboard there are also sockets 69 which are connected directly to the counters and supplemental sockets 70 which are directly 40 connected to the printing magnets without having any counter magnets associated therewith. On the upper end of the plugboard there is shown a circuit diagram of the automatic control unit. When certain columns 45 are to be used for automatic controlling, plug connections are inserted between sockets 67 and sockets 670 of the automatic control unit. From socket 680 of the control unit plug connections may be made between 680 and 68. From any plug sockets 68 connections may be made as desired to 69 and 70. It will be understood that the automatic control can be plugged in any desired columns, also that the automatic control may be plugged from 680 to 68 and thence to 70 without plugging up corresponding plug sockets 69. In this way the control number may be printed on the extra listing banks without sacrificing counter capacity when this is done. The automatic control unit is the same as heretofore em-

ployed in machines and requires no detailed description. There is an automatic control circuit 74 which extends serially through all contacts 73 of the control unit, as in the previous machine.

In the statistical work handled by tabulating machines the record cards are usually arranged in groups, each card of the group bearing a distinguishing number which serves to identify that particular group, and it is customary for the machine to indicate 75 the group number of each group for purposes of identification.

In the machine described in the previous application this group indicating was effected 80 by the regular tabulating counters or accumulators, the group number being entered into a counter from the first card of each group. Thereafter the entering of further group numbers into the counter was suppressed by means of group indicator contacts 85 which opened up after the passage of the first card.

In the present machine the use of group indicator contacts is minimized. In place of 90 entering group numbers upon a counter or counters the group number as taken from the card is arranged to directly control the printing mechanism of the machine. The feature of suppressing the entering of items into the 95 accumulator after the passage of the first card is obviated. Group numbers may or may not be entered into the accumulator, but, if entered, these group numbers will be accumulated therein, there being no suppression of 100 the accumulating of group numbers.

When this machine is used as a straight tabulator, without listing the items, it is run at a comparatively high speed but while the first card of each group is passing and the 105 group number is being printed therefrom, provision is made for running the printing attachment at the usual (slow) printing or listing speed, otherwise the mechanism would be damaged. After the first card has passed 110 and the group number has been printed the machine automatically resumes its higher speed for tabulating the remaining cards of that group.

In connection with the printing of the 115 group number in straight tabulating (non-listing) operations provision is made for printing the group number upon the record sheet only upon the passage of the first card of a group. Thereafter the normal paper feed is suppressed and when ultimately the 120 total of that group is printed it is printed in alignment with the previously printed group number. Thereafter the normal paper feed is resumed to space the paper to position to receive the new group number imprint of the 125 next group.

When the machine is set for listing, the group number is printed concurrently with 130 each listed item of that group. The group 135

number is not repeated when printing totals of listed items. The printing of all totals is effected at proper printing speed by the reset motor.

5 Referring now to Figs. 13, 17 and 18, with the resistance controlled motor type of construction the contacts shown in Figs. 13, 17 and 18 are employed in connection with the shifting lever mechanism. With list-non-list 10 lever 316 shifted to tabulating position contacts X^1 will be closed by a projection 321 which forms a part of the shifter fork, and contacts X^2 will be opened. With the lever 316 shifted to listing position contacts X^1 will be opened and contacts X^2 will be closed.

15 Fig. 18 shows other cooperating contacts which come into action when the shifter lever is in listing position. These contacts Z^1 and Z^2 are arranged to be both closed when the shifter lever is in listing position and both opened when the shifter lever is in tabulating position.

20 Referring now to Figs. 24 and 25, shaft 355 which, as previously explained, rocks only during totaling operations, is provided with 25 a depending insulating bail 355^a, which bail is arranged to normally hold open a number of non-list contacts NL^1 , NL^2 , NL^3 , NL^4 and NL^5 . Upon total-taking, shaft 355 rocks 30 clockwise (Fig. 24) and allows all of these contacts to close. The purpose of these contacts is to close circuits to the printing magnets of the various individual counters with which they cooperate and thereby allow a total to be printed of the amounts standing on 35 such counters, except when such counters carry a summation of group numbers, in which case other means are provided for preventing the printing of such amounts.

40 In the diagram, Figs. 26^a and 26^b, the tabulating motor TM is provided with a resistance 625 which can be manually adjusted by means of taps 626 to shunt out portions of the resistance as desired.

45 Referring to Fig. 26^a it will be noted that with contacts T^4 and GI^3 both open the resistance 625 will be in the armature circuit of the motor TM. With such resistance in circuit with the armature the motor will rotate 50 at a comparatively slow speed. This is the speed which is used for printing the group number from the first card. It is, however, desirable that all resistance be cut out of the armature circuit at starting to give the motor 55 sufficient torque to start the machine. How this is done will be apparent from the diagram. The diagram shows the parts in condition for starting. Here cam contact T^4 mounted in the cam box of the tabulator is shown closed. This cam contact being in circuit between binder posts 16 and 17 cuts the resistance 625 entirely out of circuit and allows the tabulator motor to start with full current and full torque. Immediately after 65 the motor has started cam contact T^4 opens

cutting resistance 625 into circuit. Inasmuch as during the first card cycle of a group cam contact GI^3 is open, the motor now continues in operation until the first card cycle is completed whereupon cam contact GI^3 closes, thus 70 shunting resistance 625 again out of circuit and permitting the motor to operate at a high tabulating speed. Due to the fact that the current through the motor is materially cut down for the first card cycle the current 75 through the clutch magnet 55 is so small that it does not hold its armature when contact C^4 was made. To obviate this difficulty contact GI^1 is provided in circuit with cam contact C^4 . Cam contact GI^1 remains open during 80 the first card tabulating cycle only and thus suppresses any action of cam contact C^4 with respect to clutch magnet 55 during this card cycle. On subsequent card cycles after the 85 group number is printed cam contact GI^1 closes and is ineffective with respect to cam contact C^4 .

90 Cam contact T^1 , opens a short time before the end of the cycle and if running at normal speed the motor TM has sufficient momentum to bring the machine to home or D position. With motor speed reduced as above for printing this momentum is not sufficient to bring the tabulator parts to home position, if the tabulator is operating on one card group, — 95 the only occasion when the motor is called upon to stop while running slow under control of resistance 625. In order to bring the tabulator to home position under these conditions a supplemental motor control circuit is 100 provided which extends from binder post 18 through cam contact L^4 through motor control relay contacts 130, through stop key contacts 87^a and back to binder post 9. Cam contact L^4 is arranged to make before cam contact T^1 opens and to break at a slightly later 105 point in the cycle thus permitting the motor TM to continue in operation for a sufficiently longer period of time to enable it to reach home position when tabulating on one card 110 group. Cam contact L^4 is operated from listing shaft 294 which is in operation at all times when tabulating and listing or when printing the first group number.

115 In the event that the tabulator is stopped by the emergency stop key 87^a when running at slow speed during the first card cycle it is desirable that means be provided for bringing the tabulator to home position. For this purpose a supplementary circuit 627 is provided extending to cam contact L^4 and connecting to a bottom contact of the emergency stop key 87^b. With emergency stop key depressed the tabulator will come to home position in the manner previously described.

120 Referring now to Fig. 26^a, contacts 250 are the usual transmission contacts (not shown) which are opened when the transmission 257 (Fig. 1) is in high speed position for tabulating and which are only closed when the 125

transmission is in low speed position for listing.

Contact X^1 is in the circuit between binder posts 10 and 12 and this contact in addition to operating with contact 250 to compel the transmission to be shifted to slow speed position for listing also have other purposes now to be described. Contact 250 is in a line extending from binder post 10 to binder post 12 which also includes contact Z^1 . When the list-non-list lever (Fig. 13) is shifted from listing position to tabulating position or vice versa, there is a period of time in the shifting of such lever when both contacts X^1 and Z^1 will be opened. This opening of contacts X^1 and Z^1 during shifting operations is utilized to compel a resetting operation.

Assume that the machine has been run with a listing setting and has stopped at the end 20 of a card group the condition of the parts will be as shown in Fig. 6. If then the list-non-list lever 316 is shifted the parts will assume the position of Fig. 3. If now the machine were restarted on the next card group 25 the contact GI^3 of the circuit diagram will not have reopened because there has been no intervening reset cycle to open them. Under such conditions the machine would restart and operate the listing mechanism under 30 high tabulating speeds. To prevent such improper operation certain circuit controlling connections are provided which will now be described.

Referring to the diagram, 84 is the magnet 35 controlling motor relay contact 130. By providing means for deenergizing 84 during a shifting operation and by compelling a subsequent resetting operation of the machine before relay 84 can be reenergized, the aforementioned objectionable starting at high speed is prevented. Referring to the diagram, circuit circuit 628 is provided from the armature of relay 91 extending through cam contact P^3 to one side of cam contact C^1 . The only way in 40 which 84 and 91 can be energized is through wire 629 to binder post 9, thence through binder post 10 to 12. By timing cam contact P^3 so that this cam contact is open when the machine is in stopped position, and inasmuch 45 as during shifting operations both contacts X^1 and Z^1 are opened at the same time there will be no path for current to flow from left side of line through 84 and thus restarting of the machine will be prevented until current 50 can be again applied to 84 after contact P^3 is closed. Contact P^3 is on total printing shaft 315 and is only operated during resetting and total printing cycles.

Inasmuch as transmission 257 is used when 55 straight listing is performed means must be provided for keeping resistance 625 from having any control of the motor during listing with the transmission shifted to listing position. Cam contact Z^2 is employed for this purpose. This cam contact closes circuit

630 which extends to a wire 631 leading to group indicator controlling magnet 92. Thus when the list-non-list lever 316 is shifted to listing position cam contact Z^2 will be closed, energizing 92 and causing contact GI^3 to be tripped and closed thus shunting out resistance 625. This contact will remain closed as long as listing continues and is only reopened upon the next resetting operation. Then after it is reopened on the next resetting operation it is again immediately closed inasmuch as 92 remains energized.

As previously explained, when running under tabulating conditions contact GI^3 closes 70 after the first card cycle. The closing of this contact is effected by means of group indicator controlling magnet 92 being energized. This magnet when the machine is running under tabulating conditions has its circuit 75 631 closed by cam contact L^3 which closes a circuit to 632 just at the end of the first card cycle. Cam contact L^3 is on the listing shaft 294 of the machine.

Inasmuch as in printing the group number from the first card of a group this group number is printed directly from the card, provision must be made for supplying current to the printer magnets during this first card group printing cycle of the machine. Referring to Fig. 21 contact GI^8 , as previously explained, is made for the first card cycle and breaks thereafter, being retained 90 broken until a new group is tabulated. This contact as shown in Fig. 26^b is in a line 633 95 extending between binder post 13 and binder post 8. The purpose of contact GI^8 is to supply current to the printer magnets which are correlated with the counter magnets if it is desired to group indicate on the columns in the printing section of the machine which 100 are coordinated with the counters. In Fig. 26^b 102 are the printer magnets. These printer magnets are connected to common bars 116. Bars 116 through wires 104 connect to the non-list contacts NL^1 , NL^2 and NL^3 , etc. Contacts NL^1 , 2 and 3, etc., as previously explained, are open at all times except when a total is printed. Therefore with 105 these contacts open it would be impossible to print the group numbers on the printer mechanism corresponding to these particular counters. If it is desired to print the group number on the field of the record corresponding to, say, bank No. 3, a switch 634 would be first closed around the non-list contacts NL^1 . 110 With this switch closed during the first card cycle and with contact GI^8 closed during the same card cycle current would be supplied to common bars 116 from binder post 13, contact GI^8 , wires 633, upper contacts P^2 now closed, line 635, contact LP^1 now closed, through switch 634 to common bar 116. In this way the magnets 102 are provided with a return path 115 for the current which, as will be understood, is a secondary circuit which has been com-

120
125
130

pleted by the energization of counter magnets from the brushes and the subsequent closing of contact 100. This counter magnet circuit will be traced for one column: from left 5 side of line, wire 82, through wire 101, contact 99, counter magnet 98 to plug socket 69, thence by plug connection to plug socket 68, thence through wire 65 to lower brushes. When an index point perforation passes the 10 lower brushes 59 current flows through these brushes, wire 95, cam contacts T^2 , T^3 , to binder post 13, wire 94, lower contacts P^4 now closed, binder post 11, through wire 636, to lower card lever contacts 64^a; to the relay 15 point of relay 85, thence to cam contact T^1 , to binder post 9, through P^5 , binder post 10, contact X^1 , to binder post 12 on other side of line 83. The energization of magnet 98 closes contacts 100 and sets up a supplemental printing circuit as follows: from left side 20 of line 82, through 101, contacts 100, printer magnet 102, common bar 116, wire 104, non-list switch 634, and through the circuit previously traced through GI^8 to left side of line. 25 It will be understood that switches 634 are only closed on the particular bank which is to be used for printing group numbers. If the tabulator is set for listing all the switches 634 will be closed on all banks in which it is 30 desired to list individual items. The same applies if particular banks are to be used for indicating group numbers when listing. If it is desired to print only totals on particular banks, corresponding switches 634 can 35 be opened. If the machine is set for listing, contacts X^2 , which are closed with such a setting of the list-non-list lever, complete the circuit to the printer magnets at all times, acting similarly to contact GI^8 except that it 40 does not open up after the first card cycle.

Contacts LP^1 , LP^2 , LP^3 , etc., are driven and actuated by or from total printing shaft 315 (Fig. 5). The purpose of these contacts is to break the circuit to the printing magnets at the end of the printing part of the reset cycle. They function similarly to contacts P^2 and P^3 in the Lake application above referred to. Upper contact P^2 whose cam is on the total printing shaft 315 is used to prevent certain objectionable back circuits during the total print cycle. The upper contact opens at the beginning of a total print cycle and closes at the end of such cycle. The lower cam contact P^2 closes at the beginning of 55 the total print cycle and opens at the end of the cycle. During total printing, current to the printing magnets 102 is supplied from right side of line 83, through non-total print switch 237, which switch has previously been closed. If it is desired to suppress the printing of totals non-total print switch 237 is opened. If a particular bank of the machine correlated to a counter is used for printing group numbers it will be understood that 60 those group numbers will be accumulated in

that counter. Obviously it is not usually desirable to print an accumulation of group numbers. Therefore, if group numbers have been indicated on a particular counter bank, after the group has been completed, it is 70 necessary that the accumulated group number be not printed. This is effected by merely opening up zero button contact 128 by zero button lever 129. With zero button shifted the counter will not be cleared but neither will the accumulated group number be printed. Before this particular counter can subsequently be used for accumulating purposes it is necessary to clear out the accumulation on group numbers from the particular counter. 75 This is done by a resetting operation prior to which resetting the switch 237 is first opened to prevent the accumulation of group numbers from being printed on the record sheet. 80

In the embodiment of the circuit diagram shown in Fig. 26^a the lower card lever contacts 64^a and 63^a correspond to card lever contacts 64 and 63 in the previous Lake application heretofore referred to with the exception that they are both operated from the lower card lever in place of operating one from the upper and one from the lower as heretofore. The purpose of lower card lever contacts 63^a and 64^a is to keep the machine running so long as cards are passing through the machine. The purpose of the single upper card lever contact 63^b which is in one of the branches 74 of the automatic control circuit is to open the control circuit 74 after the passage of the last card through the upper brushes. This will insure that the cam contact L^4 properly comes into action to bring the machine to the D (home) position. As previously explained L^4 is only operated to bring the machine to home or D position when the relays 91 and 84 (which control contacts 130) are deenergized. With the last group consisting of a single card, relay 91 would be held energized if contact 63^b were not provided. This contact under these conditions 95 will open and deenergize 91 allowing L^4 to function in a proper manner. 100

Cam contact T^5 is opened at D position and is closed at all other times in the tabulating cycle. This contact entirely cuts off the current to the upper brushes whereby they prevent blowing of fuses during plugging operation. 110

What we claim is—

1. A card-controlled printing tabulating machine for printing on record sheets data gathered from groups of cards, comprising in combination, a feeding device for said record sheets, means for first printing card group designations thereon, means for subsequently printing correlated totals of items from said groups of cards, and means for controlling the aforesaid feeding device so that said subsequently printed totals will be printed 120 125 130

- in alignment with said card group designations on said record sheet.
2. A card-controlled printing tabulating machine for printing on record sheets data gathered from groups of cards, comprising in combination, a feeding device for said record sheets, means for first printing card group designations thereon, means for subsequently printing correlated totals of items from said groups of cards, and means for suppressing the operation of the aforesaid feeding device so that said totals will be printed in alignment with said card group designations on said record sheet.
3. A card-controlled printing tabulating machine for printing on record sheets data gathered from groups of cards, comprising in combination, means for printing card group designations, and means for printing totals of items from said groups of cards upon said record sheets and in alignment with said card group designations, said total printing operation being performed subsequently to the group printing operation.
4. A card-controlled printing tabulating machine for printing on record sheets data gathered from groups of cards, comprising in combination, a feeding device for said record sheets, means for printing card group designations direct from cards while suppressing corresponding printing of totals, means for printing totals of items from said groups of cards, and means for controlling said feeding device so that said totals will be printed upon the record sheet in alignment with said card group designations.
5. A card-controlled printing tabulating machine for tabulating groups of cards and printing the totals of data gathered therefrom, comprising in combination, means to print at slow speed data from the first card of a group and means controlled by said first named means to automatically effect tabulating at higher speed of the remaining cards of the group.
6. A card-controlled printing tabulating machine for tabulating groups of cards, comprising in combination, means for printing the group designation from the first card of a group, and means for suppressing the printing of other items being concurrently derived by the tabulator from the same card.
7. A card-controlled printing tabulating machine for tabulating groups of cards, comprising means for printing the group designation from the first card of a group while suppressing the printing of other items being derived from said same card, and means for subsequently printing totals of items in said card group in alignment with said group number.
8. A tabulating machine comprising in combination, printing devices operable at comparatively slow speed and tabulating devices operable at higher speed, and electro-mechanical means for automatically changing the speed of the machine to proper printing speed whenever a printing operation is to be performed during a card cycle while cards are being tabulated.
9. In combination, a tabulating machine, a 2-speed resistance-controlled driving motor therefor, and means for automatically cutting said resistance out of circuit at completion of first card cycle.
10. In combination, a tabulating machine, a driving motor therefor, and means for automatically changing the speed characteristics of the motor upon the substantial completion of the first card cycle of the tabulating operation.
11. In a printing tabulating machine, in combination, a list-non-list setting lever for the tabulator printer, means controlled by said lever for operating said tabulator at high speed for tabulating operations, and means controlled by said lever for operating said tabulator printer at relatively low speed for listing operations, and means controlled by said lever when set for tabulating, for automatically bringing about an initial cycle of the tabulator under the relatively low listing speed conditions.
12. A combined tabulator, and printing device in which means is provided for operating the tabulator alone or the tabulator in connection with the printing device for respectively performing straight tabulating operations with total printing, or listing operations with total printing, means for setting the tabulator and printer device for either of the said operations, and means operable when the setting is for straight tabulating for bringing about an initial single printing cycle and for automatically thereafter suppressing further printing cycles until a totalizing operation.
13. A tabulator having a printing device, means for operating the same to tabulate items without printing the individual items, and means operable during such straight tabulating operations for bringing about an initial single printing cycle at the beginning of a card group and for subsequently automatically suppressing further printing cycles until totalling operations occur.
14. A tabulating device, a printing device, means for operating said devices conjointly or operating the tabulating device alone, in combination with a 2-speed driving motor therefor, and means controlled by one of said devices for temporarily automatically providing a high initial starting torque in said motor.
15. A tabulating device, a printing device, means comprising a two-speed driving motor for operating said devices conjointly or operating the tabulating device alone, a resistance for controlling the speed and torque characteristics of said motor, and a plurality

of contact devices operable by said tabulator and printing devices for controlling the coaction of said resistance and said motor to obtain the desired speed for each device.

16. A combined card tabulating and printing device, comprising group indicator contact devices operable at substantially the termination of a first card cycle of a group, and means controlled by said devices for sup-
10 pressing the mechanical operation of the printing device after said first card cycle.

17. A combined tabulator and printing device, the former being operable in conjunction with the latter or independently thereof, in combination with means to automatically effect disconnection of said printer from said tabulator after one cycle of operation thereof at the beginning of the tabulating of a card group.

18. A tabulating machine having a printing device which at times is driven in unison with the tabulator and which at times remains inactive when the tabulator is in operation, means for automatically bringing the said printing device into operation for the first card of a group, and means for subsequently suppressing the action of said printing device for the remaining cards of a group.

19. A printing tabulating device which is capable of being set for listing items or straight tabulating operation, in combination with means for effecting said settings, a 2-speed driving motor for said tabulator and means controlled by said setting means for selecting different motor speeds for straight tabulating and for listing.

20. In a tabulating machine having means for operating the same at a plurality of speeds, and means brought into operation automatically at substantially the end of the first card cycle of a group for changing said speed.

21. In a machine of the class described, in combination with devices for tabulating groups of cards, printing devices, and means for automatically printing the first card of a group at low speed and thereafter automatically running the tabulator alone at high speed.

22. In a machine of the class described having a tabulating device and a printing device and means for operating said devices conjointly or the tabulating device alone, said means including a driving motor, and means for automatically changing the speed characteristics of the motor in accordance with conjoint or independent driving of the said tabulating devices and printing devices.

23. In a printing tabulating machine having provisions for tabulating and printing items from perforated record cards, means for driving said devices, and delayed action means for varying the speed of drive after the reading of the first card of a group.

24. In a tabulating machine having provisions for analyzing groups of perforated cards and tabulating the same, means for driving said machine, and means controlled upon the passage of the first card of a group which is being analyzed for determining the subsequent driving speed for the remainder of the cards of the group. 70

25. A tabulating device, a printing device, means for operating said devices conjointly, 75 or operating the tabulating device alone, in combination with a 2-speed driving motor for said devices, and means for imparting normal low-speed low-torque characteristics to said motor when driving said printer and tabulator together. 80

26. A tabulating machine comprising in combination, printing devices operable at comparatively low speed and tabulating devices operable at higher speed, common driving mechanism for the devices including means for adapting the same to high and low speed and shifting mechanism brought into operation automatically by the operation of the machine to automatically shift from one speed to the other during continuous machine operation to adapt the speed of the driving mechanism to printing or tabulating operations in successive machine cycles. 85

27. A tabulating machine comprising in 95 combination, printing devices operable at comparatively low speed and tabulating devices operable at higher speed and shifting mechanism brought into operation automatically by the operation of the machine for automatically changing the speed of the same during continuous uninterrupted operation of the machine to proper printing speed whenever a printing operation is to be performed during a tabulating run.

28. A tabulating machine comprising in combination, printing devices operable at comparatively low speed and tabulating devices operable at higher speed, common driving mechanism for the devices, electromagnetic means for automatically shifting the speed of the driving mechanism during continuous uninterrupted operation of the machine to obtain proper driving speed when printing or tabulating operations are to be performed during a continuous run and contact devices brought into operation automatically by the operation of the machine for controlling said electromagnetic means.

29. A tabulator having a printing device with paper feeding mechanism, means for operating said mechanism to effect space by space feeding of paper, means for operating said printing device during a single tabulating cycle and for suppressing printing during other tabulating cycles and means for automatically suppressing paper feed during non-printing tabulating cycles to permit total printing in alignment with the data printed during the single printing cycle.

30. In combination a tabulating machine, a driving motor therefor having a resistance in its armature circuit, contact devices for cutting said resistance into and out of circuit and means having provisions brought into operation automatically by the operation of the tabulating machine for controlling said contact devices to cut said resistance out of circuit at starting of said motor and for a predetermined time thereafter.
31. In combination a tabulating machine, a driving motor therefor, said motor having a controlling resistance, contact devices for cutting said resistance into and out of circuit for varying the speed characteristics of the motor, and means having provisions brought into operation automatically by the operation of the tabulating machine for controlling said contact devices upon completion of a certain cycle of operations of the tabulating machine to cut said resistance into and out of circuit.
32. In a machine of the class described having in combination a tabulating machine, a driving motor therefor, means controlled by contact devices for providing high torque for said motor and means having provisions brought into operation automatically by the operation of the tabulating machine to operate said contact devices for temporarily providing high starting torque for said motor.
33. In a machine of the class described including tabulating devices and printing devices, said devices being operable conjointly or said tabulator being operable alone, means having provisions automatically brought into operation by the machine after a card cycle is completed in which printing is effected by said printing devices for effecting an increase of speed of the tabulator and suppression of operation of the printing devices.
34. The invention set forth in claim 33 in which the means for changing the motor speed is controlled by devices associated with the tabulator.
45. In testimony whereof we hereto affix our signatures.

CLAIR D. LAKE.
RALPH E. PAGE.
